CLAIM

The ornamental design for a refrigerator telescopic rack, as shown and described.

DESCRIPTION

FIG. 1 is a perspective view of a refrigerator telescopic rack showing my new design;

FIG. 2 is a perspective view of the refrigerator telescopic rack where the refrigerator telescopic rack is in an extended state;

FIG. 3 is a front elevational view of the refrigerator telescopic rack of FIG. 1;

FIG. 4 is a rear elevational view of the refrigerator telescopic rack of FIG. 1;

FIG. 5 is a left side elevational view of the refrigerator telescopic rack of FIG. 1;

FIG. 6 is a right side elevational view of the refrigerator telescopic rack of FIG. 1;

FIG. 7 is a top plan view of the refrigerator telescopic rack of FIG. 1; and,

FIG. 8 is a bottom plan view of the refrigerator telescopic rack of FIG. 1.

The broken lines in the drawings depict portions of the refrigerator telescopic rack that form no part of the claimed design.

1 Claim, 8 Drawing Sheets
